UNITED STATES PATENT OFFICE.

ALBERT GEORGE HOTHAM FERGUSON AND MEPHAN JOHN FERGUSON, OF ASCOT VALE, AUSTRALIA.

MACHINE FOR MANUFACTURING METAL PIPES.

Application filed July 10, 1922. Serial No. 574,106.

To all whom it may concern:

Be it known that ALBERT GEORGE HOTHAM FERGUSON, and MEPHAN JOHN FERGUSON, both subjects of the King of Great Britain, 5 residing at Hillcrest, Bloomfield Road, Ascot Vale, in the State of Victoria, Australia, and Falkirk, Royal Parade, Royal Park, Melbourne, in the State of Victoria, Australia, respectively, have invented certain new and 10 useful Improvements in Machines for Manufacturing Metal Pipes (for which I have filed applications in Australia, No. 1425/21, filed April 19, 1921, and in New Zealand, No. 45,979, filed June 2, 1921), of which the 15 following is a specification.

The present invention refers to steel pipes the closing or seaming of which is effected by dovetailing or up-ending the longitudinal edges and clamping same by hydraulic 20 pressure between the heads of an H-shaped bar.

Such pipes are usually constructed of two plates each curved to a semi circular form and brought and held together at diametrically opposite sides in the H-shaped locking bars mentioned. In carrying out the assembling of these four parts in readiness for 25 passage through the "closing" machine it is necessary to employ two-part bands or clips drawn together about the pipe half sections by rods and wedges which involves 30 considerable labour and equipment.

By means of the present invention the use of one locking bar can be entirely eliminated 35 with resultant reduction in cost of material, and furthermore, the assembling and labour costs are also reduced and without impairing the efficiency of the pipe produced.

According to this invention steel pipes are 40 produced by curving a single plate length into a C form leaving a single longitudinal gap to be closed by one length of locking bar.

A practical form of the machine incorporating the invention is depicted in the accompanying drawings of which Figs. 1, 2 and 3 are respectively a sectional plan, front elevation and side elevation of the parts of the machine which include the improvements.

Fig. 4 is an enlarged detail of part of Fig. 2.

Referring to the drawings it will be noted that the pipe length P consists of a single 55 plate curved into C-shape with a single lon-

gitudinal gap which pipe length with the gap uppermost is fed upon the usual cradle with the H-section locking bar L in position to the locking mechanism.

The usual mandrel 2 is provided on its 60 top with a closing tool or swage block 3, shaped to seat the bottom and corresponding flanges 4, of the locking bar L and with a bottom swage block 5 curved to correspond with the curvature of the pipe length. This 65 mandrel is slid into a pipe length and is supported on a block 6 suitably curved on top and fixed to a vertically operating hydraulic ram 7 which imparts the operating pressure.

The upper head and flanges 8 of the locking-bar L are acted upon by a rigidly fixed 70 swage block 9 on a superimposed backing 10 rigidly fixed to a cross strut 11 of the frame.

In order to prevent twisting of the locking bar L and to straighten same, its upper head 8 is caused to travel between a pair of rollers 12 formed at the bottom with flanges 13 which enter the grooves 14 in the locking 80 bar as in Fig. 4 said rollers being in front of the locking mechanism.

The rollers 12 are mounted on the lower ends of vertical bars 114 formed with slots 15 to permit vertical adjustment and to vary 85 the position and gripping effect of the rollers, said bars being pivoted upon bolts 16 passed through said slots into the frame member 11.

A forked rod 18 is fixed by a pin 19 to each 90 vertical bar and the rods extend in opposite directions at approximately right angles to said bars and pass freely through holes 20 formed in supporting bars 21 their ends being screw threaded to take adjusting nuts 22. 95

It will be noted that the fork attached to one vertical bar embraces the other vertical bar and that by loosening the nuts 22 the rollers 12 can be adjusted to suit the size 100 of pipe being made.

In front of the locking mechanism are a pair of freely rotatable vertical guide rollers 23 arranged a distance apart each being formed with a concave periphery to conform to the contour of the pipe length which 105 latter is fed between said rollers to cause its longitudinal edges 24 to approach each other and fit tightly up to the grooves of the H-section locking bar.

The spindle 32 of each roller is mounted 110

upon a heavy **U** plate frame 25 supported upon a platform 26 and engaging guides 27 thereon said frame having a screw 28 passing through a bar 29 and provided with 5 a nut 30 formed with a hand wheel 31 for turning the screw to horizontally adjust the rollers according to the size of the pipe being made.

The spindle 32 of each roller passes 10 through an upper bush 33 and into a lower bush 34 both of which are screwed through the horizontal members 35 of the frame while the lower one 34 passes through a slot 36 in the platform 26 to permit vertical adjustment. The bushes 33 and 34 are 15 adjusted according to the size of rollers being used.

It is found advantageous to have the locking bar **L** on one longitudinal edge of the 20 pipe and in that position to feed the pipe between the rollers 23 with the locking bar in engagement with the flanges of the rollers 12 when the vertical operation of the ram as the pipe length advances causes the **H**- 25 section bar to be locked to the edges of the pipe length by the pressure of the swage blocks.

We claim:—

1. A machine for swaging the flanges of 30 grooved locking bars to the opposing longitudinal edges of curved pipe blanks, comprising supporting means for the locking-bars, and means to press the longitudinal edges of the blanks into the grooves of the 35 bars.

2. A machine for swaging the flanges of grooved locking bars to the opposing longitudinal edges of curved pipe blanks, comprising supporting means for the locking- 40 bars, means to press the longitudinal edges of the blanks into the grooves of the bars, and means to swage said flanges onto the edges of the pipe blanks.

3. A machine for swaging the flanges of 45 grooved locking bars to the opposed longitudinal edges of curved pipe blanks, comprising rolls engaging the grooves of the locking bars and means to press the longitudinal edges of the pipe blanks into said 50 grooves.

4. A machine for swaging the flanges of grooved locking bars to the opposed longitudinal edges of cylindrical pipe blanks,

comprising a pair of supporting rolls having flanges adapted to engage the grooves of the 55 locking-bars, and rollers for engaging the pipe blanks adapted to press the longitudinal edges of the latter into the grooves of the locking bars.

5. A machine for swaging the flanges of 60 grooved locking bars to the opposed longitudinal edges of cylindrical pipe blanks, comprising a pair of supporting rolls having flanges adapted to engage the grooves of the locking bars, means to adjust the rolls vertically and laterally, and rollers for engaging the pipe blanks adapted to press the longitudinal edges of the latter into the grooves of the locking bars.

6. A machine for swaging the flanges of 70 grooved locking bars to the opposed longitudinal edges of cylindrical pipe blanks, comprising means for supporting the locking-bars, and guide rollers having concave peripheries conforming to the contour of 75 the pipe blanks adapted to press the edges of the latter into the grooves of the locking bar.

7. A machine for swaging the flanges of grooved locking bars to the opposed longitudinal edges of cylindrical pipe blanks, comprising means for supporting the locking-bars, guide rollers having concave peripheries conforming to the contour of the pipe blanks adapted to press the edges 85 of the latter into the grooves of the locking bar, and means to laterally and vertically adjust the rollers.

8. In a machine for swaging grooved locking bars to the longitudinal opposing 90 edges of cylindrical pipe blanks, a pair of concave rolls for guiding the blank, laterally adjustable supporting frames for the rolls, means for adjusting the rolls in the frames, a pair of rollers having flanges engaging 95 the grooves of the connecting bars, means for vertically adjusting the rollers, means for laterally adjusting the latter, a mandrel within the pipe blank, a swage block carried by the mandrel beneath the locking bar, a 100 fixed swage bar above the latter, and means for raising and lowering the mandrel.

Dated this 26th day of May 1922.

ALBERT GEORGE MOTHAM FERGUSON.
MEPHAN JOHN FERGUSON.
